DRAFT RIGGING

Hubert L. Spence and William J. Metzger, East Cleveland, Ohio, assignors to National Malleable and Steel Castings Company, Cleveland, Ohio, a corporation of Ohio

Application October 18, 1946, Serial No. 704,188

12 Claims. (Cl. 213—36)

1

The invention relates to friction draft gears, having particular reference to mine car applications although not restricted to this alone.

It is an object of our invention to provide a compact draft gear of high capacity in relation to its size, and which has very few parts.

A further object is to provide a draft gear which will meet the limited space requirements of mine car construction while providing effective cushioning of draft and buffing shocks.

Another, and particular, object is to provide a draft gear which dispenses entirely with the need for retaining bolts or other special parts for locking the several elements of the gear in assembled relationship for shipment and/or operation.

An additional object is to provide a draft gear having dual-function interchangeable parts whereby the same part not only can be used in alternative locations but will serve two purposes in either location, thus considerably reducing the number of different parts required.

Other objects and advantages of our invention will appear as the description proceeds.

In the drawings which illustrate a preferred embodiment of our invention:

Fig. 1 is a plan view of a draft gear constructed in accordance with the invention, illustrating its application to mine cars, and Fig. 2 is a side elevational view thereof.

Figs. 3 and 4 are detail views to enlarged scale of one of the friction shoes of the gear, Fig. 3 being a top plan view thereof (considered in its relation to the assembled draft gear) and Fig. 4 an end elevational view thereof.

Fig. 5 is an end elevational view of the follower wedge and Fig. 6 a central horizontal sectional view thereof. These views are drawn to a somewhat reduced scale compared with Figs. 1 and 2.

Fig. 7 is a detail top view of the friction stem and Fig. 8 is a side elevational view thereof.

Fig. 9 is a central horizontal longitudinal sectional view of the draft gear, with the friction shoes and friction stem shown in full, illustrating the manner of assembling the draft gear.

Fig. 10 is a view similar to Fig. 9 but illustrating the position of the parts as completely assembled and compressed to the dimensions of the draft gear pocket.

Our invention comprises in its general arrangement a friction stem 11, friction shoes 12 for engagement with the friction stem, a follower wedge 13 having inclined wedge surfaces 14 for engagement with the friction shoes, and spring means 15 for opposing movement of the shoes along the friction stem, the friction stem having

2

a shouldered end 16 for limiting movement of the shoes, the follower wedge having a central opening 17 to clear the shouldered end of the friction stem during assembly therewith, and the follower wedge and friction shoes having coacting projections 18 and grooves 19 cooperating with the shouldered end of the friction stem to hold the follower wedge and shoes against removal.

In our preferred construction there are two sets of friction shoes for engagement with opposite ends of the friction stem, a follower wedge for engagement with each set of friction shoes, and a compression spring 15 arranged between the two sets of friction shoes. The follower wedge adjacent the shouldered end 16 of the stem has the central opening 17 referred to in the preceding paragraph and the follower wedge and friction shoes have the interlocking projections and grooves as described, these projections and grooves being arranged to permit their assembly with the friction stem when the spring is compressed and thereafter to hold them against removal from the friction stem. We prefer that the follower wedge adjacent the head 20 be of the same construction as the one which is adjacent the shouldered end 16 of the stem so that the two will be interchangeable. In this case the two sets of friction shoes likewise will be constructed in the same manner and be interchangeable. Thus the follower wedges and shoes constitute dual-function interchangeable parts whereby the same part not only can be used in alternative locations but will serve two purposes in either location, thus considerably reducing the number of different parts required. The two functions of the wedges and shoes are their coaction in creating frictional resistance to compression of the draft gear in draft and buffing, and their coaction in holding the parts of the draft gear in assembled relationship without the use of retaining bolts or other special locking parts.

The shouldered end 16 of the friction stem provides means for limiting movement of the shoes in one direction, and it will be observed that the follower wedge is constructed and arranged to pass over the end of the friction stem during assembly therewith. The interlocking means provided by the projections 18 of the follower wedge and the grooves 19 of the shoes hold the follower wedge in assembled relationship with the friction stem and friction shoes. The interlocking portions of the wedge and shoes are arranged at an angle to the axis of the friction stem as clearly shown in Fig. 10 for example, providing locking

surfaces on the friction shoes which, in the assembled position of the friction stem, wedge and shoes, engage portions of the follower wedge to hold it against removal.

The coacting projections and grooves 18, 19 are constructed and arranged to slide into engagement as the follower wedge is passed over the end of the friction stem as indicated in Fig. 9, and as will be described in greater detail hereinbelow.

Referring now more particularly to Fig. 1, we have shown in dot-dash outline a draft gear pocket including the front draft lugs 21 and rear draft lugs 22 against which the ends of the gear abut. The head 20 of the friction stem 11 is constructed and arranged for attachment to a coupler shank as by means of the projections 23, 24 through which a vertical coupling pin 25 extends. Portions of the coupler shank (not shown) extend between projections 23 and 24 for engagement by the coupling pin 25.

In the preferred construction illustrated, the friction stem 11 and the shouldered end 16 thereof are generally circular in shape. The ends of the stem are slightly tapered as shown in Fig. 7, the stem being somewhat wider at the center than at its ends. Each of the friction surfaces 26 is cylindrical in form with the axis of the cylinder slightly inclined to the longitudinal centerline of the friction stem.

The friction shoes 12 are formed with concave cylindrical surfaces 27 corresponding in shape with the convex friction surfaces 26 of the stem, and also are formed with flat wedge faces 28 for engagement with the flat wedge surfaces 14 of the follower wedges. On each side of the shoe is a groove 19 to which reference has been made, these grooves being formed substantially parallel with the wedge face 28.

The follower wedge 13 is shown in detail in Figs. 5 and 6. It is generally rectangular in shape, the opening 17 thereof being defined by the edges of the wedge surfaces 14 and the arcuate portions 29 which are formed to clear the shouldered end 16 of the friction stem. The projections, or lugs 18, are arranged substantially parallel with the wedge surfaces 14, their positions in relation to the grooves 19 being shown in Figs. 1 and 10. On the top and bottom of the wedge are formed outwardly extending reinforcing and supporting flanges 30 (Figs. 2, 5 and 6) projecting outwardly from the wedge adjacent the central opening 17. These flanges reinforce the wedge adjacent the opening 17 and also provide broad supporting surfaces for engagement with draft gear supports as will be understood from Fig. 2.

The method of assembling the draft gear is illustrated in Fig. 9. The steps are as follows: The friction stem 11 is placed on end on the assembly bench and one of the follower wedge members 13 is lowered into place against the back end of the head 20 of the stem. A pair of the friction shoes 12 is entered into the wedge in a diagonal direction so that the retainer lugs 18 of the wedge enter the grooves 19 in the sides of the shoes. After the shoes are in position, the spring 15 is lowered onto them and a pair of spring compressing clamps 31 is arranged to grip the spring near its upper end and compress it almost to its solid height.

While the spring is thus held under compression, the upper pair of friction shoes 12 is placed between the spring and upper follower member 13 in the angular position shown in Fig. 9. The

upper wedge is then lowered onto the shoes, the retainer lugs 18 on the wedge entering the grooves 19 in the shoes. The shoes are then tipped into position against friction stem 11, the retainer lugs 18 completely entering the grooves and the follower wedge finally seating on the shoes with the wedge faces 14 in the engagement with the wedge faces 28 of the shoes. The spring clamps 31 are then removed, releasing the spring which forces the ends of the shoes into tight engagement with the shouldered end 16 of the stem. In Fig. 10 the parts are shown approaching this position as there remains a slight clearance *a* between the ends of the shoes and the shouldered end 16 of the stem. Fig. 10 is a horizontal sectional view based on the position of the parts as illustrated in Figs. 1 and 2 and thus shows the parts compressed to an extent sufficient to fit the draft gear pocket between the lugs 21 and 22. However it will be understood that when not so compressed the upper pair of shoes 12 will come up against the shouldered end 16 of the stem. In that position the friction stem, shoes and wedge are interlocked and the wedge cannot be removed. For replacement of parts the spring can be compressed as illustrated in Fig. 9, permitting disassembly by reversing the order of assembly described above.

The operation of the assembled draft gear is as follows:

Under a pull load the coupler moves the friction stem to the left as viewed in Figs. 1 and 2. The first movement takes up the small amount of clearance at *a* between the end of the friction stem and the rear friction shoes 12. After that clearance has been taken up, the friction shoes are moved to the left with the follower wedge 13 and compress the spring 15. The forward friction shoes 12 are held stationary by the forward wedge 13 abutting the forward draft lugs 21. This wedge therefore presses the forward shoes against the friction stem and friction is generated as the friction stem moves relatively to those shoes. The taper of the friction surfaces 26 of the stem forces the friction shoes laterally apart against the wedging forces set up by the forward wedge 13, thus generating an increased amount of friction. At the end of the travel of the friction stem, the ends of the two pairs of shoes 12 come into contact with one another, thus limiting further compression of the draft gear.

During this pulling movement, the retaining lugs 18 on the rear wedge 13, cooperating with the grooves 19 in the rear friction shoes, serve to carry the rear wedge forward with the shoes, thus holding it in proper position at all times.

In buffing the action is similar to that in pulling except that the rear friction shoes are the ones which are held stationary and the friction stem 11 moves rearwardly in relation to them.

The preferred draft gear construction which we have described is intended primarily for service on cars in the coal mine field. In many of these mines the cars are turned upside down, one or two at a time, without uncoupling them from the train. It is therefore necessary that the coupler, and with it the friction stem 11 to which the coupler is attached, shall be able to rotate around a longitudinal axis. It is for this reason that we prefer to make the friction stem of generally cylindrical shape so that it can rotate while the friction shoes and wedges remain stationary relative to the car. Generally the draft gear will be applied only to one end of a car so

that its coupler will normally be coupled with a non-rotatable coupler of an adjacent car whereby, after a car has been turned upside down and returned, the couplers will return to the correct position for angling in a horizontal direction. The head 20 may be formed with flattened surfaces adjacent flanges 30 for engagement therewith to prevent rotation of stem 11.

The terms and expressions which we have employed are used in a descriptive and not a limiting sense, and we have no intention of excluding such equivalents of the invention described, or of portions thereof, as fall within the purview of the claims.

We claim:

1. A railway draft gear comprising a friction stem, friction shoes for engagement with the friction stem, a follower wedge for engagement with the friction shoes to wedge them against the friction stem, and spring means for opposing movement of the shoes along the friction stem, the friction stem having means for limiting movement of the shoes in one direction, the follower wedge being constructed and arranged to pass over the end of the friction stem during assembly therewith, and the follower wedge and friction shoes having interlocking means which cooperate with said limiting means to hold the follower wedge in assembled relationship with the friction stem and friction shoes.

2. A railway draft gear comprising a friction stem, friction shoes for engagement with the friction stem, a follower wedge for engagement with the friction shoes to wedge them against the friction stem, and spring means for opposing movement of the shoes along the friction stem, the friction stem having means for limiting movement of the shoes in one direction, the follower wedge being constructed and arranged to pass over the end of the friction stem during assembly therewith, and the follower wedge and friction shoes having interlocking portions arranged at an angle to the axis of the friction stem.

3. A railway draft gear comprising a friction stem, friction shoes for engagement with the friction stem, a follower wedge for engagement with the friction shoes to wedge them against the friction stem, and spring means for opposing movement of the shoes along the friction stem, the friction stem having means for limiting movement of the shoes in one direction, the follower wedge being constructed and arranged to pass over the end of the friction stem during assembly therewith, and the friction shoes having locking surfaces which, in the assembled position of the friction stem, wedge and shoes, engage portions of the follower wedge to hold it against removal.

4. A railway draft gear comprising a friction stem, friction shoes for engagement with the friction stem, a follower wedge for engagement with the friction shoes to wedge them against the friction stem, and spring means for opposing movement of the shoes along the friction stem, the friction stem having means for limiting movement of the shoes in one direction, the follower wedge being constructed and arranged to pass over the end of the friction stem during assembly therewith, and the follower wedge and friction shoes having coacting projections and grooves constructed and arranged to slide into engagement as the follower wedge is passed over the end of the friction stem and to be retained in engagement by coaction with the spring and aforesaid limiting means.

5. A railway draft gear comprising a friction stem, friction shoes for engagement with the friction stem, a follower wedge having inclined wedge surfaces for engagement with the friction shoes, and spring means for opposing movement of the shoes along the friction stem, the friction stem having a shouldered end for limiting movement of the shoes, the follower wedge having a central opening to clear the shouldered end of the friction stem during assembly therewith, and the follower wedge and friction shoes having coacting projections and grooves cooperating with the shouldered end of the friction stem to hold the follower wedge and shoes against removal.

6. A railway draft gear comprising a friction stem having substantially cylindrical friction surfaces, friction shoes having complementary friction surfaces for engagement with the friction surfaces of the stem, a follower wedge for engagement with the friction shoes, and spring means for opposing movement of the shoes along the friction stem, the friction stem having a shouldered end, the follower wedge having a central opening to clear the shouldered end of the friction stem during assembly therewith, flanges projecting outwardly from the follower wedge adjacent said central opening, and the follower wedge and friction shoes having interlocking projections and grooves.

7. A railway draft gear comprising a friction stem having substantially cylindrical friction surfaces, friction shoes having complementary friction surfaces for engagement with the friction surfaces of the stem, a follower wedge for engagement with the friction shoes, the follower wedge and friction shoes having coacting projections and grooves, and spring means for opposing movement of the shoes along the friction stem, the shoes having portions extending into the spring means, the friction stem having a shouldered end, the follower wedge having a central opening therethrough to clear the shouldered end of the friction stem during assembly therewith, and flanges projecting outwardly from the follower wedge adjacent said central opening.

8. A railway draft gear comprising a friction stem, two sets of friction shoes for engagement with opposite ends of the friction stem, a follower wedge for engagement with each set of friction shoes to wedge them against the friction stem, and a compression spring arranged between the two sets of friction shoes, the friction stem having a shouldered end, the follower wedge adjacent the shouldered end having a central opening to clear said shouldered end during assembly therewith, and the follower wedge and friction shoes adjacent the shouldered end having interlocking projections and grooves inclined to the axis of the friction stem for assembly of the wedge and shoes with the friction stem when the spring is compressed and for holding them against removal from the friction stem when the spring is released.

9. A railway draft gear comprising a friction stem, two sets of friction shoes for engagement with opposite ends of the friction stem, a follower wedge for engagement with each set of friction shoes to wedge them against the friction stem, and a compression spring arranged between the two sets of friction shoes, the friction stem having a shouldered end, the follower wedge adjacent the shouldered end having a central opening to clear said shouldered end during assembly therewith, and the follower wedge and friction shoes adjacent the shouldered end having inter-

locking projections and grooves inclined to the axis of the friction stem for assembly of the wedge and shoes with the friction stem when the spring is compressed, and for holding them against removal from the friction stem when the spring is released, the spring being constructed to surround portions of the friction shoes.

10. A railway draft gear comprising a friction stem, two sets of friction shoes, for engagement with opposite ends of the friction stem, a follower wedge for engagement with each set of friction shoes to wedge them against the friction stem, and a compression spring arranged between the two sets of friction shoes, the friction stem having a shouldered end, the follower wedges having central openings to clear said shouldered end during assembly with the friction stem, and the follower wedge and friction shoes adjacent the shouldered end having interlocking projections and grooves inclined to the axis of the friction stem for assembly of the wedge and shoes with the friction stem when the spring is compressed and for holding them against removal from the friction stem when the spring is released.

11. In a railway draft gear, a friction stem having an enlarged end, a follower wedge having a central opening to clear said enlarged end, a spring, and friction shoes extending into the spring, the follower wedge and shoes having co-acting projections and grooves, said grooves be-

ing inclined to the axis of the friction stem for angular assembly of the friction shoes to bring the shoes and wedge into interlocking position with the shoes inside the enlarged end of the friction stem.

12. In a railway draft gear, a friction stem having an enlarged end, a follower wedge having a central opening to clear said enlarged end, friction shoes, and spring means surrounding portions of the shoes, inwardly projecting lugs in said central opening, and inclined grooves in the friction shoes for engagement with said lugs, the engaging lugs and grooves in conjunction with the spring means maintaining the parts in assembled relation.
